UNITED STATES PATENT OFFICE.

HARRY N. MIDDLETON, OF WESTVILLE, NEW JERSEY, ASSIGNOR TO B. F. STURTEVANT COMPANY, OF HYDE PARK, MASSACHUSETTS, A CORPORATION OF MASSACHUSETTS.

CONVEYER SYSTEM.

Application filed February 18, 1921. Serial No. 446,000.

To all whom it may concern:

Be it known that I, HARRY N. MIDDLETON, a citizen of the United States, residing at Westville, in the county of Gloucester and

5 State of New Jersey, have invented certain new and useful Improvements in Conveyer Systems; and I do hereby declare the following to be a full, clear, and exact description of the invention, such as will enable 10 others skilled in the art to which it appertains to make and use the same.

The present invention relates to conveyer systems, and more particularly to systems employing conduits or pipes through which 15 the material is carried by a current of air.

In such systems it is often desirable to provide for the delivery of the material at one or another point, as circumstances may require, and conduits or pipes are accordingly provided leading from the main supply pipe with suitable switch dampers, so-called, whereby the material may be directed into the desired conduit or pipe. Difficulty has heretofore been experienced in providing a switch damper which, when set to direct the material into one delivery pipe, effectually prevents the escape of air or material into the other conduit, particularly where material of a finely divided nature is being handled, and which is free from all liability of catching or holding any long or stringy material being conveyed, such as cotton or wool, with the possibility of blocking the system.

30 It is one of the objects of the present invention to devise a construction of pipes or conduits and switch damper whereby material may be directed into one or another of the delivery pipes or conduits without loss or leakage of material or air. Another object of the present invention is to provide a construction of pipes and switch damper having no projecting parts or edges upon 35 which material of a long or stringy nature, such as cotton or wool, can catch and be held.

With these and other objects in view, the present invention consists of the devices and combination of devices and arrangement of parts hereinafter described and more particularly defined in the claims.

In the accompanying drawings which illustrate what is now considered to be the preferred embodiment of the present inven-

tion, Fig. 1 is a top sectional view on lines 1-1 of Fig. 2, showing a supply conduit or pipe and two delivery conduits or pipes, with a switch damper for directing the material through either one or the other of the delivery pipes; Fig. 2 is a side elevation looking in the direction of the arrow 2-2 in Fig. 1; and Fig. 3 is a perspective on an enlarged scale of the switch damper.

In the construction illustrated in the drawings the material is conveyed from some source of supply by means of a current of air through a pipe 4 in the direction indicated by the arrow, and is directed into one or the other of the delivery pipes 5 and 6, as desired.

These supply and delivery pipes, as is the custom, are circular in cross section but at their ends 7, 8, and 9, respectively, adjacent the switch damper, are substantially square in cross section.

These ends of the supply and delivery pipes are joined by a closed or air-tight connection 11 of truncated, wedge shape, having flat top and bottom, 12 and 13. The rear side, as viewed in Fig. 1, is provided with an opening surrounded by the out-turned flange 14 and closed by the plate 15, the flange of which is bolted to the flange 14. The front face adjacent the supply pipe is bowed or curved, as shown at 16.

Mounted within the connection 11 is the switch damper illustrated in Fig. 3. It comprises the top 20, side walls 21 and 22, and bottom 23, having its ends open. It is pivotally mounted within the connection 11, being fixed upon a shaft 24, which is pivoted in the connection 11 and has the actuating handle 25 extending from its lower end. A convenient method of mounting the switch damper upon the shaft 14 is by bending the side 21 back upon itself and riveting it as at 27.

The side 22 of the switch damper projects rearwardly beyond the side 21 being curved as at 29 in the arc of a circle, of which the axis of shaft 24 is the center. The curved portion 29 has a loose fit within the curved portion 16 of the wall of the connection 11. The delivery end of the switch damper is also curved or arc-shaped, as shown at 31, the center of curvature being the axis of shaft 24.

In order that there may be no surface edges upon which the material may be caught or held, the square section 7 of the supply pipe 4 is extended into the connection 5 11 and enters the receiving end of the switch damper. Thus the bottom 33 of the supply pipe overlies the bottom 23 of the switch damper, and the sides 34 and 35 overlie the edges of the side walls 21 and 22 of the 10 switch damper. The top of the section 7 underlies the top 20 of the switch damper. The material in passing from the supply pipe into the switch damper meets no edges upon which it can catch. The projection of 15 the top, bottom and sides of the supply pipe into the switch damper is of such extent that these parts still enter the receiving end of the switch damper when the latter is adjusted to divert the material into the delivery 20 pipe 5, as shown in dotted lines in Fig. 1.

To prevent material being lodged upon the edge 37 where the converging walls of the delivery pipes or sections 8 and 9 meet, the delivery end of the switch damper is 25 made of slightly less width than the widths of the receiving ends of the delivery pipes, so that in whichever position the switch damper may be set, the side wall adjacent the edge 37 will always be off-set slightly 30 towards the medial line of the pipe or conduit into which the material is to be delivered.

In order that the switch damper may be actuated easily from one position to the 35 other, clearance must be given between the delivery end of the switch damper and the edge 37 where the side walls of the delivery pipes or conduits meet. To prevent leakage of fine or powdered material and of air 40 through this clearance space, flexible canvas strips 39 have been provided which are riveted to the delivery edges of the side walls 21 and 22, projecting therefrom a short distance.

45 These flexible strips extend over and close this clearance space, engaging the inner surface of the side wall of one conduit when the switch damper is in position to discharge material into the other conduit. The flexibility of the strips permits them to bend and yield sufficiently to allow the delivery edge of the side wall of the switch damper to be moved slightly past the edge 37 of the delivery pipes.

50 The removable plate or closure 15 is not only a convenience in assembling the apparatus, since it permits the piping, including the section 11, to be erected first and then the switch damper to be placed in position, but it also affords easy access to the interior of the connection 11 for the purpose of inspection or repair.

In operation it is only necessary to swing 55 the handle 25 from one extreme position to the other in order to change the switch

damper and divert the stream of material from one delivery conduit or pipe into the other.

Having thus described the present invention, what is claimed is:

1. In a conveyer system, a supply pipe having adjacent its discharge end one side wall arc-shaped as viewed in longitudinal section, a pair of intersecting delivery pipes having their top, bottom and side walls extended to the supply pipe to form a closed connection therewith, a switch damper located within said connection and comprising a four wall section having open ends, one of the walls adjacent the receiving end 70 being arc-shaped to fit the arc-shaped supply pipe, the damper being pivotally mounted adjacent the receiving end on the side opposite from the arc-shaped wall, and means for swinging the damper to bring 75 one or the other of its side walls into contact with one or the other of the extended side walls of the delivery pipes to cause the discharge end of the damper to register with 80 one or the other of the delivery pipes. 85

2. In a pneumatic conveyer system a supply pipe, a plurality of delivery pipes, a closed section connecting the supply and delivery pipes and having an arc-shaped wall, a switch damper mounted within the closed 90 section and having top, bottom and side walls and open receiving and discharging ends, one of said walls being arc-shaped to fit the arc-shaped wall of the connecting section, the damper being pivoted at the 95 receiving end and fitting closely the connecting section, the supply pipe extending into the receiving end of the damper, and means for moving the damper to bring its discharge end into register with one or another of the delivery pipes. 100

3. In a pneumatic conveyer system, a supply pipe, a plurality of delivery pipes, a closed section connecting the supply and the delivery pipes, a switch damper located 105 within the closed section, and consisting of top, bottom and side walls with open ends, and pivoted at its receiving end, the top, bottom and side walls of the supply pipe entering the open end of the switch damper, the side walls of the delivery end of the switch damper being provided with flexible strips for closing the opening between the walls of the switch damper and of the delivery pipes to prevent the escape of air or material, and means for moving the damper. 110

4. In a pneumatic conveyer system, a supply pipe, a pair of delivery pipes, a section having top, bottom and side walls connecting the supply pipe and the delivery pipes, a switch damper located within said connection and consisting of top, bottom and side walls with open ends and pivoted at its receiving end at one side thereof, the supply pipe extending into the said section and 115 120 125 130

entering the open end of the switch damper, the discharge end of the switch damper being of less width than the receiving ends of the delivery pipes, and means for closing 5 the clearance joint between the switch damper and the delivery pipes to prevent the escape of air or material.

5. In a pneumatic conveyer system a supply pipe, a pair of delivery pipes, a closed 10 section connecting the supply and delivery pipes and having side walls aligning with the outer or non-adjacent side walls of the pair of delivery pipes, a switch damper mounted within the section having top, bottom and side walls and open ends and providing a straight passage for the air and material, the receiving end of the damper fitting closely within the closed connecting section adjacent the supply pipe with the 15 end of the supply pipe extending into the open end of the switch damper and the discharging end of the damper fitting closely one or another of the delivery pipes with a side wall of the damper engaging a side 20 wall of the connection, and means for moving the switch damper to direct the material from the supply pipe into one or another of the delivery pipes.

6. In a pneumatic conveyer system a supply pipe, a pair of angularly disposed delivery pipes having their receiving ends arranged in a single arc as viewed in longitudinal section and with their adjacent side walls joining, a closed section connecting 25 the supply and delivery pipes, such section having its side wall adjacent the supply pipe of arc shape as viewed in longitudinal section, a switch damper mounted within the section having top, bottom and side 30 walls and open receiving and discharging

ends, one side wall adjacent the receiving end being arc-shaped as viewed in longitudinal section and of substantially the same radius of curvature as the arc-shaped wall of the connecting section, the damper being 45 pivotally mounted within the section at the center of curvature of the arc-shaped walls, the end of the supply pipe entering the open receiving end of the switch damper, the discharging end of the switch damper being 50 arc-shaped as viewed in longitudinal section and of substantially the same radius of curvature as the arc-shaped ends of the delivery pipes, the pivot of the damper being the center of curvature, the discharging 55 end of the damper being of slightly less transverse width than the width of the opening of the delivery pipes, and the side walls of the damper at the discharging end having flexible strips to close the clearance opening 60 between the end of the switch damper and the junction of the adjacent side walls of the delivery pipes.

7. In a pneumatic conveyer system, a supply pipe having an arc-shaped side wall 65 adjacent its end, a pair of intersecting delivery pipes, a switch damper having top, bottom and side walls and open receiving and discharging ends, a side wall adjacent 70 its receiving end being arc-shaped to fit closely the arc-shaped side wall of the supply pipe, a pivot for the damper at its receiving end at one side thereof opposite from the arc-shaped wall, the discharge ends of oppositely disposed walls of the damper 75 being equidistant from the axis of the pivot so that each wall may fit closely the junction of the adjacent walls of the delivery pipes, and means for moving the damper.

HARRY N. MIDDLETON.
